[57] CLAIM

The ornamental design for a package for flattened balloons, as shown and described.

DESCRIPTION

FIG. 1 is a front elevational view of a package for flattened balloons showing my new design;

FIG. 2 is a rear elevational view thereof;

FIG. 3 is a right side elevational view thereof; the left side elevational view being a mirror image thereof; and,

FIG. 4 is a bottom plan view thereof.

FIG 1

FIG 3

FIG 2

FIG 4
